UNITED STATES PATENT OFFICE

JOSEPH RENTLER, OF COLUMBUS, OHIO

ILLUMINATED MAIL BOX

Application filed October 19, 1928. Serial No. 312,610.

This invention relates to illuminated mail boxes, the principal object of the invention being to provide a simple and convenient device of this character which may be secured 5 to or inserted in wall of the home, and having means therein to light the face of same wherein are inserted glass members to bear such data as is required.

Further, the invention seeks to provide a 10 mail box of the foregoing character that may be economically and expeditiously stamped from sheet metal, which is simple, durable and inexpensive in construction and pleasing in appearance.

15 Other advantageous features of the invention will be fully understood from the following description when the same is considered in connection with the accompanying drawings, forming part of this specification, 20 in which:—

Figure 1 is a front elevation of the mail box with the face frame removed showing the construction of the lighting compartment.

25 Figure 2 is a front elevation, with the face frame in place, showing its general outline.

Figure 3 is a cross section of the face frame showing its construction, and method of securing the glass members therein.

Figure 4 is a top view, parts being broken 30 away to show both the lighting and mail compartments.

Figure 5 is an end view showing the door with a mail receiving slot formed therein.

Figure 6 is a cross sectional view on line 35 A, A, showing the construction of the mail box when mounted in and secured in an opening in a wall.

Figure 7 is a front elevation of the mail box mounted in a wall having an opening 40 therein for the reception of same.

Like numerals of reference indicate like parts throughout the several views.

Referring to the drawings the sheet metal casing 1, is divided into a lighting compartment 2 and a mail compartment 3, by the partition 4, which is provided with an aperture 5, and secured in place in the casing by the angles 6, 6, or other suitable securing means. In the lighting compartment is a suitable 45 lighting fixture 7 and an electric lamp 8,

The lamp is positioned approximately opposite the aperture in the partition, the purpose being to allow the light to pass through into the mail compartment to illuminate the same. The mail compartment is provided with a door 9, suitably hinged as at 10, and provided with a lock 11, and a knob 12. It will be noted that the door is inclined from the perpendicular, the object being to allow the door to be held in a closed position by gravity. Suitable lugs having apertures 13, 13 are formed integral or otherwise with the casing to receive screws or other suitable fastening devices. The casing is provided with a detachably secured face frame 14, and is divided by a horizontal bar 17, this bar may be integral or otherwise with the frame, to provide openings 15 and 16. It will be noted that these openings may be of different areas. Secured to the horizontal bar is a T shaped member 21, its purpose being to secure the glass members 18 and 19 in place in the frame. The glass members may bear such data as is required, for instance the name of the owner and his house number. The glass may be made up 55 of sections, each section bearing the desired numeral or letter. The face frame is detachably secured to the casing by means of screws or otherwise 20, 20. The mail compartment 60 may be provided with a mail receiving slot 21 in the top wall as shown in Fig. 4, or may 65 have an opening in the door as at 22 shown in Figure 5, for the same purpose.

The construction shown in Figure 6 in cross section, and in Fig. 7 in elevation may be used 75 when the mail box is mounted in a recess in a wall. The face frame is constructed with a mail receiving opening 23 and the same is closed by a door 24, hinged to the frame as at 25, 25, the door is provided with, an integral 80 or otherwise, hook 26 adapted to provide a means to lift the same. It will be noted that the face frame may be provided with a flange 27, adapted to trim the opening in the wall X 85 on the outside. The box is secured in the opening by means of screws 28, 28. The section 29 is telescopically adjustable in the casing to provide adjustment for the different 90 thickness of wall encountered in the various buildings. The section 29 is provided with a 100

hinged door 30, and a lock 31, and a knob 32. This section is also constructed with a flange 33 adapted to trim the opening in the wall on the inside. The door is adapted to close the mail compartment. In Fig. 4 it will be noted that the partition is deflected to provide additional space for the hand to enter the mail compartment. In Fig. 6 the partition is deflected as shown or substantially so to provide a passage for the mail into the mail compartment. Wires 34 are provided for attachment to a suitable supply of electric current for lighting purposes. The mail may be inserted into the box by lifting the door on the end of the mail compartment if desired. It is believed that the operation of the mail box as a whole will be clear, in view of the foregoing description which has been given in connection with the construction of same. Although the preferred form of the invention has been herein illustrated and described, it is understood that various changes and modifications may be made within the scope of the invention as defined by the appended claim.

What I claim is:

Illuminated mail box, in combination with a wall, electrically lighted, comprising substantially a lighting compartment with a lamp mounted therein, an adjacent mail compartment, an interposed deflected apertured partition, said partition being deflected to provide an entrance into the mail compartment, a flanged face frame detachably secured to said box having a plurality of openings formed therein, above the upper one of which adjacent the top is formed a horizontally extending slot for mail reception, a closure for said opening, a flanged section telescopically adjustable in said box, a door hinged to said section, and means to secure the unit to place.

In testimony whereof, I hereunto affix my signature.

JOSEPH RENTLER.
